CLAIM

The ornamental design for a battery, as shown and described.

DESCRIPTION

FIG. 1 is a perspective view of a new design for a battery; FIG. 2 is a front view thereof; FIG. 3 is a rear view thereof; FIG. 4 is a right side view thereof; FIG. 5 is a left side view thereof; FIG. 6 is a top view thereof; and, FIG. 7 is a bottom view thereof.

The broken lines shown in the drawings depict environmental structure or portions of the article that form no part of the claimed design.

The battery is shown with a symbolic break in its height. The appearance of any portion of the article between the break lines forms no part of the claimed design.
